DESIGN FOR A MEDICINE CABINET SHELF

Vincent J. Spano, Vallejo, Calif.

Application December 6, 1947, Serial No. 143,006

Term of patent 7 years

(Cl. D33—3)

To all whom it may concern:

Be it known that I, Vincent J. Spano, a citizen of the United States, residing at Vallejo, in the county of Solano and State of California, have invented a new, original, and ornamental Design for Medicine Cabinet Shelf, of which the following is a specification, reference being had to the accompanying drawings, forming part thereof.

Fig. 1 is a perspective view of a medicine cabinet shelf, showing my new design.

Fig. 2 is a side elevational view of same.

Fig. 3 is a top plan view of same.

Fig. 4 is a front elevational view of same.

Fig. 5 is a bottom plan view of same.

I claim:

The ornamental design for a medicine cabinet shelf, as shown.

VINCENT J. SPANO.
